UNITED STATES PATENT OFFICE.

F. AUGUSTUS SCHULTZ, OF MOUNT PLEASANT, IOWA.

DESIGN FOR BUCKLE AND RING.

Specification forming part of Design No. 5,054, dated June 27, 1871.

To all whom it may concern:

Be it known that I, F. AUGUSTUS SCHULTZ, of Mount Pleasant, in the county of Henry and in the State of Iowa, have invented certain new and useful Improvements in Design for Combined Buckle and Ring; and do hereby declare that the following is a full, clear, and exact description thereof, reference being had to the accompanying drawing and to the letters of reference marked thereon making a part of this specification.

The nature of my design is fully illustrated by the accompanying drawing; and it consists in a buckle with ring attached, for use on harness, or for any other purpose.

A represents the frame of the buckle, with the

cross-bar B, upon which the tongue C turns. The sides of the frame A are extended, forming the ring D, while at or near the ends of the cross-bar B on the frame are upward-projecting ears *a a*, connected by a cross-bar, E, for passing the end of the strap under.

What I claim is—

The design for a buckle, with ring attached, as shown and described.

In testimony that I claim the foregoing I have hereunto set my hand and seal this 2d day of May, 1871.

F. AUGUSTUS SCHULTZ. (L. S.)
